CLINKER REMOVING DEVICE

William Gaughrin, Chicago, Ill.

Application May 21, 1937, Serial No. 143,872

16 Claims. (Cl. 110—40)

This invention relates to furnaces and more particularly to clinker removing devices therefore, although certain features thereof may be employed with equal advantage for other purposes.

It contemplates more especially the provision of improved clinker removing attachment in combination with a fuel carrier to insure clinker free operation therewith.

10 Clinkers are a constant source of interruption and annoyance in fuel feeding devices and result in thermal losses unless the fuel grate and feeding devices are kept clear thereof. Clinker removing devices are utilized in conjunction with 15 fuel grates, especially of the moving fuel feeding type as set forth in United States Letters Patent 1,622,312 dated March 29, 1927. The carrier for the clinker removing member is preferably in the form of a horizontal endless conveyor 20 chain having a suitable support for guiding and effecting its travel along a predetermined path to introduce fuel such as coal into the combustion space of a furnace. The clinker removing members are preferably provided adjacent the opposite sides of the fuel grate so as to contact the 25 base portions of the clinkers as the grate traverses its predetermined path of travel in supplying fuel for combustion purposes.

One object of the present invention is to provide 30 improved clinker removing devices in connection with coal burning furnaces.

Another object is to provide a clinker removing 35 expedient of improved construction and operation.

Still another object is to provide a clinker 40 breaking knife that is adjustably connected to a fuel grate conveyor for displacement therewith.

A further object is to provide a clinker breaking attachment to a fuel grate for permanent connection therewith.

45 A still further object is to provide a clinker breaking knife that is pivotally connected to a grate so as to clear any obstructions in the path of movement.

Still a further object is to provide a clinker 50 breaking knife that is operatively connected to a fuel grate so as to be collapsibly associated therewith to clear obstructions in the path thereof.

An additional object is to provide pivotally connected clinker breaking knives in conjunction 55 with fuel grates together with means for normally maintaining such in an operative condition and displaceable to an inoperative position by obstructions in the path thereof.

Other objects and advantages will appear from 60 the following description of an illustrative embodiment of the present invention.

In the drawings:

Figure 1 is a side view in elevation of a preferred embodiment embodying features of the

present invention in connection with an endless chain grate, parts thereof being broken away to clarify the showing.

Figure 2 is a sectional plan view taken substantially along line II—II of Figure 1.

Figure 3 is a fragmentary sectional view taken substantially along line III—III of Figure 2.

Figure 4 is a fragmentary sectional end view in elevation of a modified embodiment of the present invention, the grate link sustaining rollers 10 being dispensed with.

Figure 5 is an enlarged side view of an end link with a clinker breaking knife attached thereto in a manner embodying features of the present invention, parts thereof being broken away and 15 shown in section to clarify the showing.

Figure 6 is a plan view of the device shown in Figure 5.

Figure 7 is a sectional view taken substantially along line VII—VII of Figure 5.

Figure 8 is a perspective view of a modified clinker removing member shown permanently attached to a link.

Figure 9 is a perspective view of a still further modified form of a clinker removing device that is detachably associated with a link of the fuel grate.

Figure 10 is a perspective view of a chain link of the type shown in Figure 2.

Figure 11 is a perspective view of a spring used 30 in conjunction with the clinker breaking knife.

The structure selected for illustration comprises a furnace of any suitable construction or design having confining walls 10—11 and 12—13 to define a combustion chamber. The particular 35 shape of the combustion chamber may vary in size and design within a wide range depending upon the dictates of commercial practice and the requirement of any particular installation. The furnace is provided with a fuel grate that preferably though not essentially consists of an endless chain 14 formed of a plurality of links 15 and 16 defining alternate series of endless constituent chains having their link extremities interconnected by means of pivoted rods 17 and 18, respectively. 40

It is worthy of note that the alternate series of interconnected links 15 and 16 are disposed in advance of each other for one-half of the link length with the pivoted rods 17 and 18 connecting the 50 extremities of the link series 15 and 16 that are independent of each other to impart thereto the desired flexibility for linear drums in a manner that will appear more fully hereinafter. The length of the link series defining endless adjacent 55 chains 15 and 16 as well as the number that are alternately disposed in adjacent relationship in advance of each other depends upon the size of the combustion chamber.

It is worthy of note that the individual links 60

15 and 16 which are identical in structure and shape, are provided with a linear series of alternately disposed notches 19 and 20 (Figure 10) along the side edges thereof to provide a free path for the draft air to pass upwardly therethrough. The lateral extreme sides of the endless chain conveyor defined by the links 15 and 16 that are pivotally connected in tandem and laterally of each other in alternate series, are provided with 10 a series of links 21 which are interconnected with the intermediate link series 16 by the extremities of their pivot rods 17 and 18, the links 21 on both sides of the endless chain 14 being of identical construction and carry clinker breaking knives 22 in a manner which will appear more 15 fully hereinafter.

The outside links 21 travel adjacent the side walls of the combustion chamber of the furnace 10 so as to be disposed in the path of the clinkers 20 formed therein. The clinker breaking knives 22 consist, in this instance, of an elongated bar of substantially rectangular cross-section. The top surface of the bar 22 has converging surfaces 23 and 24 (Figure 7) that define a sharp cutting edge 25 along a longitudinal median line thereof for substantially its entire length except for the forward extremity 26. As shown, the clinker breaking knives are pivoted at their forward extremity 26 to a pin 27 that extends transversely through the forward region of the outside links 21 that are preferably though not essentially of tubular construction and formation to receive the knife 22 therein through an opening 28 provided in the top surface 29 thereof.

35 In order to urge the knife 22 in its extreme counter-clockwise position (viewed from Figure 5), a coil spring 30 envelops the extremities of the pin 27 on both sides of the knife extremity 26 that is reduced to provide a hub 31 so that it 40 may accommodate coil spring extremities 32 within the interior of the links 21 (Figure 7). The coil extremities of the spring 30 terminate in linear extensions 33 that contact the forwardly curved interior 34 of the link 21 (Figure 5), 45 thereby urging the intermediate straight portion 35 of the spring 30 against the underside of the knife 22 to elevate such to its extreme operative counter-clockwise position (Figure 5).

Should the knife 22 meet an obstruction constituting a part of the frame structure of the fuel grate 14, the spring 30 will permit the pivotal displacement of the knife 22 to its collapsed or inoperative position substantially shown in dotted outline in Figure 5 within the interior of the links 21. It is worthy of note, however, that the knife 22 will not be deflected to its inoperative position by the mere resistance offered by a clinker that may be in the path of the knife edge 25 thereof. The encounter of the longitudinal series of knives 22 with the clinkers forming along the side walls of the furnace serves to effect the breaking or disintegration thereof. The disintegrated clinkers are carried along by the grate 14 to the ash pit 36 as will appear more 55 fully hereinafter.

70 The pivot pins 27 that sustain the knives 22 are threaded to the links 21 having a side opening 27' communicating with the tubular interior of the links 21, thereby affording the assembling and dismantling of the knives 22 with their springs 30 within the side links 21 of the endless grate 14. An opening 27" may be provided in the bottom of the side links 21 in order to permit any foreign substances such as parts of the 75 disintegrated clinkers to pass therethrough

should such become lodged within the tubular interior thereof. In order to sustain the traverse of the endless conveyor grate 14, the latter is mounted on a frame 37 having transverse shafts 38 and 39 bridging side plates 40 and 41 thereof. The shafts 38 and 39 carry traction wheels 42 and 43 just inwardly of and adjacent to the exterior side frame plates 40 and 41 that support a pair of rails 44 that enable the frame 37 with its endless grate 14 to be displaced along 10 a linear path within the combustion chamber 10 of the furnace to effect the complete removal thereof should occasion arise therefor.

As shown, the frame 37 together with its side plates 40-41 carry drums 45 and 46 journaled on shafts 47 and 48 carried by the frame 37. It is to be noted that the shaft 48 is mounted in adjustable blocks 49 disposed in horizontal guides 50 near the forward extremity of the frame 37. Threaded rods 50 extend from vertical members 52 to engage the blocks 49 so as to effect their adjustment along horizontal guides 50. To this end, the forward drum 46 is adjustable within the limits of threaded rods 51 that have lock nuts 53 and 54 provided thereon to maintain the blocks 49 in any adjusted position. As shown, the drums 45 and 46 are provided with sprocket teeth 55 circumferentially spaced over the surface thereof to engage the extremities of the links 15 and 16 adjacent the pivotal shafts 17 and 18 thereof to effect their traverse along an endless path defined by the drums 45 and 46.

In order to sustain the endless conveyor 14 and drums 45 and 46 in an effort to avoid sagging, a 35 plurality of rollers 56 and 57 are carried by the shafts 58 and 59, respectively, that bridge the side plates 40 and 41 of the frame 37 to define a horizontal series of upper and lower rollers 56 and 57. It is worthy of note that the lower series of rollers 57 are in the path of the forwardly disposed clinker breaking and removing knives so that it is necessary for the latter to ride thereover in their collapsed position within the tubular links 21. With this arrangement, the clinker knives 22 assume their operative inclined position responsive to the urge of the spring 30 beyond the limits of the lower series of rollers 57 and the shafts 39 and 38 supporting the frame 50 wheels 42 and 43.

As described herein, the clinker removing members are preferably in the form of steel knives 22 having convergent surfaces 23 and 24 which intersect in a sharp linear breaking edge 25. These are mounted only on a series of outside links 21 pivotally connected in tandem by pivot rods 18 at each side of the endless chain 14. The clinker removing members are preferably assembled with the chain grate links 15 and 16 laterally alternated in a series of laterally disposed chains connected abreast and in tandem by the pivot rods 17 and 18, respectively, to define the endless chain grate 14. The travel thereof is normally in a clockwise direction (viewed from Figure 1) and such is effected by means of a worm wheel 60 attached to the drum supporting shaft 47 to impart clockwise rotation thereto. The rotation imparted to the drum 45 is intermittent and is rendered possible through the worm 61 carried by the transverse shaft 62 journaled in bearings 63 mounted to the frame 37 in any associated manner.

The worm 61 meshes with the worm wheel 60 and intermittent rotation is imparted to the transverse shaft 62 by means of a stub shaft 64 75

- that is geared thereto by means of intermeshing bevel gears (not shown) confined in a housing 65 which is an extension of a housing 66 that envelops the worm wheel 60 described supra.
- 5 The housings 65—66 are attached to the side plate 40 of the frame 37, and intermittent rotation is imparted to the stub shaft 64 by means of a bell crank lever 67 attached thereto so that the short arm 68 thereof may carry a pawl 69
- 10 pivotally attached to the extremity 70 thereof. The pawl 69 cooperates with a ratchet wheel 71 attached for rotation with the sub shaft 64 that is intermittently operated responsive to the oscillations of the bell crank lever 67.
- 15 The bell crank lever 67 is oscillated responsive to a rod 72 terminating in a knuckle 73 that affords adjustable attachment to the bell crank lever 67 through the medium of an elongated slot 74 therein. The strike of the bell crank lever 67
- 20 is adjusted by varying the position of attachment of the knuckle 73 along the length of the slot 74 so as to vary and control the speed of intermittent rotation imparted to the driving drum 45. The rod 72 is pivotally connected at its upper extremity (not shown) to a crank arm (not shown) that is rotated by an electric motor mounted on any suitable part of the furnace 10 or an extension of the frame 37.

As a result of the continuous rotation of the motor (not shown), intermittent rotation is imparted to the worm 61 so as to cause comparatively slower intermittent rotation of the worm wheel 60 that is affixed to the shaft 47 supporting the drum 45 for movement therewith. It

35 must be borne in mind that the linear travel of the endless fuel conveyor 14 is comparatively slow to meet the requirements of fuel combustion.

In the modified embodiment shown in Figure 4, the transverse shafts 58 and 59 together with 40 the moving chain grate supporting rollers 56 and 57, respectively, are dispensed with and provided with horizontally confronting tracks 75 provided on the interior sides of the side plates 40' and 41'. The end links 21' are sustained by the confronting horizontal tracks 75 to preclude the necessity of having the rollers 56 and 57 disposed between the side plates 40 and 41 (Figures 1 and 2). With this arrangement, it is not necessary to provide the pivotally mounted clinker 50 breaking knives 22 so that a modified form thereof may be resorted to in such instances.

To this end, a modified form of knife 22' (Figure 8) may be integrally mounted on the end links 21' without any requirement to render such 55 movable or collapsible in any position of grate travel along the entire path thereof. In such instance, the end links 21' may be of solid construction rather than tubular as shown in connection with the embodiment illustrated in Figures 1 to 3 inclusive.

In the still further modified embodiment shown in Figure 9, the clinker breaking knives 22'' are formed integral with a base 76 having a tongue projection 77 extending downwardly therefrom to 65 cooperate with a complementary groove 78 provided longitudinally in the top surface 79 of the end links 21''. With this arrangement, the clinker breaking knives 22'' are inserted in the link grooves 78 while the chain grate links 21'' turn about the outward sprocket drum 45 to render such accessible for that purpose. As the chain grate 14 is caused to travel in its normal direction, these knives 22'' whose cutting edges 70 are parallel with and close to (but not touching) the side walls of the furnace 10, will engage the

clinkers at their base portions and remove them. The clinkers will lodge upon the grate 14 and will be deposited at the rear end thereof upon the furnace floor. When the links 21'' which carry the clinker removing knives 22'' have been turned by the inward drum 46 to a sufficient extent, the knives 22'' will slide along the grooves 78 from the links 21'' so that when the grate chain 14 moves sufficiently further, the clinker removing knives 22'' will fall away from the 10 grate chain 14 onto the furnace floor. The knives 22'' are, therefore, prevented from coming into engagement with the grate supporting rollers 57 and shafts 38—39 that support the furnace chain grate structure or into engagement with any other part of the grate structure. When clinkers again form, the knives 22'' which already have been retrieved from the furnace floor by means of suitable hooks or tongs having long handle members, are readily replaced as 20 soon as the chain grate 14 has passed the obstructions presented by the transverse rollers 57 as well as the shafts 38 and 39 carrying the carriage supporting wheels 42 and 43.

With such a construction, the knives 22'' are 25 detachably associated with the links 21'' to prevent removal during their movement along the upper horizontal stretch of the endless grate 14 to feed and sustain the coal and enable their removal from the grate links 21'' upon reversal 30 of the grate 14 direction. Thus, the chain grate 14 is then free to proceed along the lower inoperative stretch of traverse in a repeated cycle of intermittent grate moving operations. Various changes may be made in the embodiment of the 35 invention herein specifically disclosed without departing from or sacrificing any of the advantages of the invention or any features thereof, and nothing herein shall be construed as limitations upon the invention, its concept or structural embodiment as to the whole or any part thereof except as defined in the appended claims.

I claim:—

1. In a device for removing clinkers from the side walls of furnaces, the combination with an 45 endless fuel conveyor comprising interconnected links, of clinker removing means movably connected to the end links defining the side edges of said endless conveyor, said clinker removing means being fixedly connected in linear alignment to said end links against removal during the operation of said conveyor.

2. In a device for removing clinkers from the side walls of furnaces, the combination with an 50 endless fuel conveyor comprising interconnected links, of clinker removing means pivotally connected to the end links defining the side edges of said endless conveyor, said clinker removing means being connected in linear alignment to said end links against removal during the operation of said conveyor.

3. In a device for removing clinkers from the side walls of furnaces, the combination with an 55 endless fuel conveyor comprising interconnected links, of clinker removing means pivotally connected to the end links defining the side edges of said endless conveyor, said clinker removing means being connected in linear alignment to said end links against removal during the operation of said conveyor, and spring means for 60 urging said clinker removing means to normally assume an operative position.

4. In a device for removing clinkers from the side walls of furnaces including an endless traveling conveyor for feeding fuel along a predeter- 70

mined path for progressive combustion in said furnace, clinker removing members associated with certain links of said endless conveyor, said clinker removing means being in the form of a knife having an end portion secured to the conveyor and a clinker cutting edge portion extending upwardly from said conveyor links, the conveyor links and clinker removing member having complementary tongue and groove formations interacting to prevent separation of said conveyor links and clinker removing members when said member is in the upper stretch of the conveyor to enable said members to effect removal of clinkers and permitting said member to fall from the conveyor upon reversal in the direction of travel of the conveyor.

5. Apparatus for removing clinkers from the side walls of furnaces including an endless traveling conveyor having upper and lower stretches and a clinker removing member upon said conveyor, the conveyor and clinker removing member having tongue and groove formations interacting to prevent separation of said conveyor and member when said member is in the upper stretch 10 of the conveyor to enable said member to effect removal of clinkers and permitting said member to fall from the conveyor upon reversal in the direction of travel of the conveyor.

6. In a device of the character described, the combination with a flexible fuel grate, of means for moving said fuel grate along a predetermined path to feed coal into a furnace, and movably mounted means on the side edges of said grate in the path of formed clinkers to effect the disintegration and removal thereof.

7. In a device of the character described, the combination with a flexible fuel grate, of means for moving said fuel grate along a predetermined path to feed coal into a furnace, movably mounted means on the side edges of said grate in the path of formed clinkers to effect the disintegration and removal thereof, and means for resiliently maintaining said last named means in operative position and to permit the displacement thereof to an inoperative position for clearance purposes.

8. In a device of the character described, the combination with a flexible fuel grate, of means for moving said fuel grate along a predetermined path to feed coal into a furnace, movably mounted means on the side edges of said grate in the path of formed clinkers to effect the disintegration and removal thereof, and means for resiliently maintaining said last named means in operative position and to permit the displacement thereof to an inoperative position for clearance purposes.

9. In a device of the character described, the combination with a flexible fuel grate, of means for moving said fuel grate along a predetermined path to feed coal into a furnace, linear series of movably mounted means on the side edges of said grate in the path of formed clinkers to effect the disintegration and removal thereof, and means for resiliently maintaining said last named means in operative position and to permit the displacement thereof to an inoperative position for clearance purposes.

10. In a device of the character described, the combination with a flexible fuel grate, of means for moving said fuel grate along a predetermined path to feed coal into a furnace, linear series of movably mounted means having knife

edges pivotally mounted on the side edges of said grate in the path of formed clinkers to effect the disintegration and removal thereof, and means for resiliently maintaining said last named means in operative position and to permit the displacement thereof to an inoperative position for clearance purposes.

11. In a device of the character described, the combination with an endless grate comprising a series of interconnected links in flexible association, the side edges of said grate comprising links having a substantially flat surface, there being an elongated groove in the top surface of said last named links, said groove communicating with an end of said links, and clinker removing means slidably mounted in the groove of said last named links.

12. In a device of the character described, the combination with an endless grate comprising a series of interconnected links in flexible association, the side edges of said grate comprising links having a substantially flat surface, there being slots in the top surface of said last named links, and clinker removing means movably mounted in the slot of said last named links.

13. In a device of the character described, the combination with an endless grate comprising a series of interconnected links in flexible association, the side edges of said grate comprising links having a substantially flat surface, there being slots in the top surface of said last named links, and clinker removing means pivotally mounted in the slot of said last named means.

14. In a device of the character described, the combination with an endless grate comprising a series of interconnected links in flexible association, the side edges of said grate comprising chambered links having a substantially flat surface, there being slots in the top surface of said last named links in communication with the chambered interior thereof, and clinker removing means pivotally mounted in the slot of said last named means.

15. In a device of the character described, the combination with an endless grate comprising a series of interconnected links in flexible association, the side edges of said grate comprising chambered links having a substantially flat surface, there being slots in the top surface of said last named links in communication with the chambered interior thereof, clinker removing means pivotally mounted in the slot of said last named means, and spring means mounted within said tubular links to engage said clinker removing means to normally maintain the latter in operative position.

16. In a device of the character described, the combination with an endless grate comprising a series of interconnected links in flexible association, the side edges of said grate comprising chambered links having a substantially flat surface, there being slots in the top surface of said last named links in communication with the chambered interior thereof, clinker removing means pivotally mounted in the slot of said last named means, and spring means mounted within said tubular links to engage said clinker removing means to normally maintain the latter in operative position, there being a side opening in said tubular links to enable the assembling and dismantling of said spring means.

WILLIAM GAUGHRIN.
